INVENTOR:
BY his ATTORNEY:
A. M. Carlsen.

UNITED STATES PATENT OFFICE.

LARS B. HALVERSON, OF SIOUX FALLS, SOUTH DAKOTA.

POSTING-TRAY.

1,346,886.

Specification of Letters Patent. Patented July 20, 1920.

Application filed February 19, 1919. Serial No. 278,091.

To all whom it may concern:

Be it known that I, LARS B. HALVERSON, a citizen of the United States, residing at Sioux Falls, in the county of Minnehaha 5 and State of South Dakota, have invented a new and useful Posting-Tray, of which the following is a specification.

My invention relates to improvements in posting trays, and the main object is to provide a posting tray adapted for use by banks in posting checks and deposit slips in the ledger, though the tray may also be used by other business houses for posting in the ledger the daily transaction of each customer. Another object is to provide a posting tray with resilient guards about the papers placed on the tray, the resiliency admitting freedom of the hand in placing and removing the papers. A third object is to 20 provide a posting tray with paper guards or keepers that will admit light from all sides in upon the papers placed on the tray.

In the accompanying drawing:

Figure 1 is a face view of the improved 25 tray with some papers on it, looking in the direction of the arrow in Fig. 2. Fig. 2 is a side elevation of Fig. 1, shown in position for service. Fig. 3 is an enlarged section on the line 3—3 in Fig. 2, showing clearly the 30 construction of the lower end of each leg of the resilient arches, or the lower end of the resilient post 22. Fig. 4 shows the upper portions of several pages of a ledger to be posted from the papers on the tray.

Referring to the drawing by reference numerals, 5 designates the body of the tray and may be made of wood or other suitable materials; the lower end of said body board is supported on two soft cushions 6, so as 40 not to scratch the table 7. The other end is supported by a suitable prop 8, which is pivoted at 9 to the ends of a cross cleat 10, which is fixed to the board and provided with wings 11 for the prop to stop against 45 when swung into supporting position. 12 is a cushion at the point of the prop contacting with the table. The upper side of the board is provided with two finger grooves, 13, to enable the operator to readily pick up 50 the papers nearest to the board.

15 designates a pile of checks and 16 the deposit slips placed with their upper ends between the checks, all ready to be posted in the ledger, and 15^a and 16^a designate some 55 of the checks and deposit slips turned upside down and placed farther up on the tray

after they have been posted. To retain or guard said piles of checks and slips in said places, the board is provided with several rigid wire arches 17, which are secured in 60 the board by having their legs threaded and provided with two nuts, 18, 19, one above and the other below the board. The board is also provided with arches 20, made of resilient coil springs and having their legs 65 secured to the board by headed screws 21 (see Fig. 3) passed upwardly through holes in the board and screwed into the legs, the coils of said legs forming the threads for the screw to engage in and hold the arch-leg 70 upright. The flexible post 22 is likewise secured to the board, and has its top end closed by a short screw, whose round head 23 forms the top of the post. At 20^x in Fig. 2 is shown how those spring arches may be 75 forced into mostly any shape so as to give room for the hands handling the checks and slips, and when the hands are removed the arches will resume normal position. The same is the case with the post 22. And light 80 is admitted freely upon the papers 15, 16, not only from above but also laterally through the open arches.

In the operation the tray is raised by the prop 8 to a suitably inclined position and 85 placed near the book-keeping machine, such as is of late years common in banks and large business houses, for posting upon detachable sheets of the ledger, say like the pages 50, 60, 70 and 80 in Fig. 4, the business 90 transactions of a day, or since the last posting took place.

Now the book keeper, having arranged all the deposit slips face up in the pile 16 and all checks face up in the pile 15, in such an 95 order that each depositor's checks rest upon his deposit slip or slips in the pile 16, the operator proceeds as follows: If the check on the top of the pile is signed by A. B., he puts sheet 50 in the machine (as the account 100 of A. B. is found on that page) and after writing or printing thereon the date and checks, say \$7, \$5 and \$13, he cannot help finding as the next document the deposit slip, from which he marks down, say \$100, 105 as shown, and as there was an earlier balance of \$50, the new balance is put down as \$125. So far as the tray is concerned it makes no difference whether the writing in the ledger is done by hand or by a more or 110 less perfect machine. Said page 50 being thus completed and the checks and deposit

slips relating to that account turned up side-down at 15^a—16^a, the next check found at the top of pile 15—16, if signed say, C. D., refers to the account of that depositor on page 60; said page is then likewise posted, as shown, by posting the \$25 in the deposit column and making the new balance \$100, below the old balance, \$75.

The next paper in the check pile 15 may 10 be signed E. F., and is entered on page 70, as shown. On page 80 is shown how the same customer or depositor, G. H., may have made two deposits in one day, in which case the new balance, \$90, is placed in the 15 same line as the last deposit.

It is evident that for other business than

banking, the items shown on the drawing under "checks" may represent merchandise sold to the customer, and the items indicated under "deposits" may represent payments made on the account. 20

What I claim is:—

A posting tray having paper guards formed of coil-springs and shaped as arches; said arches having their legs secured to the 25 base of the tray by screws passed through the base and screwed into the spring coils forming the lower ends of the legs of the arches.

In testimony whereof I affix my signature. 30

LARS B. HALVERSON.
